Patented Nov. 21, 1916.

THE NORRIS PETERS CO., PHOTO-LITHO., WASHINGTON, D. C.

UNITED STATES PATENT OFFICE.

CHARLES J. KINDEL, OF GRAND RAPIDS, MICHIGAN, AND JOSEPH DELANEY, OF BROOKLYN, NEW YORK.

BED-BOTTOM WIRE FABRIC.

1,205,642.

Specification of Letters Patent.

Patented Nov. 21, 1916.

Application filed February 28, 1916. Serial No. 80,838.

To all whom it may concern:

Be it known that we, CHARLES J. KINDEL and JOSEPH DELANEY, citizens of the United States, respectively residing at Grand 5 Rapids, county of Kent, and State of Michigan, and Brooklyn, county of Kings, State of New York, have invented certain new and useful Improvements in Bed-Bottom Wire Fabrics, of which the following is a specification.

This invention relates to woven-wire bed-bottoms, and contemplates the production of a wire-fabric which, preferably, shall possess the desired amount of resiliency and, 15 at the same time, an inherent limit to undue sagging.

The invention, therefore, consists in the formation and combination of parts, preferably of spring-wire, for the purposes 20 specified, substantially as hereinafter set forth and particularly pointed out in the claims.

Referring to the drawing: Figure 1 is a fragmentary view in plan of my improved 25 wire-fabric bed-bottom; Fig. 2 a similar view of one of the principal links in detail; and, Figs. 3 and 4 illustrate two modifications of the principal links.

Similar numerals of reference indicate 30 similar parts in all the figures of the drawing.

The fabric is composed of a number of parallel series of principal links longitudinally disposed and connected. For the purpose of illustration, we have shown three 35 such series, the same being numbered, respectively, 5, 6 and 7. The links of the series, or what we term, for convenience, the principal links, are indicated at 8, and the 40 minor or cross-links, employed for joining the principal links of a series with the corresponding links of the adjacent series, are indicated at 9.

The link 8 is formed by bending a blank 45 of, preferably, spring-wire upon itself, and at its middle, to form a flat coil 8^a, two turns of the blank constituting a sufficient coil. At each side of the coil occur terminals or legs 10, and these preferably extend from 50 said coil at opposite sides thereof and practically in the same plane, the planes being varied merely by the thickness of the wire. Between their ends, the terminals are outwardly and oppositely bowed, and if formed 55 of spring-wire, said terminals will straighten

under stress until straight and practically parallel which, will, of course, be their limit of expansion. The bowing of these terminals may be increased or diminished from that shown. The legs 10 finally terminate in abrupt hooks 11, those of one pair of 60 terminals or legs engaging the coil or eye 8^a of the next succeeding link of the series.

The cross-links, or as we have termed them, the minor-links, may be of any desired form, but are preferably capable of yielding, and therefore, formed of a blank of spring-wire bowed or curved sufficiently to result in the desired amount of resiliency in the finished fabric. Each cross or minor-link terminates in abrupt hooks 12, which engage the eyes or coils 8^a of the adjacent 70 principal links of adjacent series.

Both the cross or minor-links and also the principal-links are capable of modification 75 without sacrificing the advantages of our invention, and as an illustration, we have illustrated in Figs. 3 and 4 of the drawing, two simple modifications of such principal-links. In Fig. 3, the terminals or legs cross 80 immediately below the eye or coil, as indicated at 10^a, while in Fig. 4, the terminals or legs are positioned close together immediately below the eye or coil by means of abrupt reentrant curves 10^b. However, in 85 any of these forms of principal-links, and also in many others that may be readily devised upon this principle, the longitudinal resiliency is limited by the legs or terminals straightening under stress, after which, no 90 further sagging of the fabric can occur. Upon a removal of the stress, the legs or terminals, as will also the cross- or minor-links, will resume their normal or bowed condition.

Having described our invention, what we 95 claim is:

1. A wire fabric bed-bottom, consisting of a plurality of similarly and longitudinally disposed straight parallel series of principal-links, each link of said series consisting of a piece of spring-wire coiled upon itself at its middle to form an eye and extended beyond the same to form plain bowed terminals extending in the same direction as 100 and inclosing said eye, said terminals terminating in hooks, the two hooks of each pair of terminals engaging the same eye of the next succeeding link of the same longitudinal series, and cross-links, terminating in 105 110

hooks, engaging those eyes of the opposite links of adjacent series with which the terminals of the principal-links engage.

2. A wire fabric bed-bottom, consisting of 5 a plurality of similarly and longitudinally disposed straight parallel series of principal-links, each link of each series consisting of a piece of spring-wire coiled upon itself at its middle to form an eye and extended 10 beyond the same to form plain oppositely bowed terminals extending in the same direction as and inclosing said eye, said terminals terminating in hooks, the two hooks of each pair of terminals engaging with the 15 same eye of the next succeeding link of the same longitudinal series, and bowed cross-

links, terminating in hooks, engaging those eyes of the opposite links of adjacent series with which the terminals of the principal-links engage.

20 In testimony whereof we affix our signatures in the presence of two witnesses.

CHARLES J. KINDEL.
JOSEPH DELANEY.

Witnesses as to signature of Charles J. Kindel:

CLYDE SEIPLE,
WILBUR F. BRINK.

Witnesses as to signature of Joseph De-
laney:

E. ELLIS,
C. P. COOPER.
